MOUNTINGS FOR AUTOMATIC WEAPONS
Franz Horn, Dusseldorf-Nord, Germany, assigner to
Firma Rheinmetall G.m.b.H., Dusseldorf, Germany
Filed Dec. 3, 1962, Ser. No. 241,875
Claims priority, application Germany Dec. 5, 1961
3 Claims. (Cl. 89—36)

The invention relates to the installation and mounting of a machine gun or similar weapon, mounted movably in recoil, but otherwise rigidly in turrets, for example in the rotating turrets of armoured cars.

In armoured vehicles it is frequently desirable to fit, in addition to the gun, also a rigidly fixed machine gun to provide sufficient firing power also for shorter distances. However, this machine gun must be fixed so that it may recoil and the mounting should be gas-tight, that is to say, tight against powder smoke and gases, whilst allowing at the same time a wide range of vertical and lateral adjustment. In addition, installation and dismantling should be possible quickly and easily.

In a known mounting for a machine gun, the barrel is located at the muzzle end longitudinally displaceably in a sleeve which expands conically towards the outside, and which is mounted in turn by means of a screwed sleeve and a spherical annulus. This spherical annulus serves as forward pivot bearing and is located in turn in the wall of the turret by means of special divided sleeves, adapted in shape to the spherical configuration. The machine gun housing is not, however, movable in recoil.

The manufacture of associated spherical surfaces and counter-supports is rather expensive; furthermore, also the mounting and dismantling of the weapon become very difficult. In addition, with a plurality of components, arranged one within the other, summation of the manufacturing tolerances results in inaccuracies, and the presence of a plurality of sliding, mutually movable parts leads to increased wear which affects, in turn, the accuracy of the weapon.

According to the invention, these drawbacks may be avoided, and the requirements made regarding the installation of the weapon may be fulfilled in that the pivot bearing or mounting forms a part of the recoil booster or the like, and has the shape of an externally spherical annular shoulder surrounding the same, and mounted universally movably and axially displaceably in a cylindrical bore in the wall of the turret or the gun shield.

The characteristic feature of the mounting according to the invention is its simplicity, eliminating sleeves, ball mounting, spherical shells, and the like, which require special fitting during the subsequent installation.

Preferably, the annular shoulder is mounted immediately behind the lateral outlets for the powder gases on the recoil booster.

Furthermore, in a preferred embodiment of the invention, the annular shoulder may have towards the front an arcuate recess so that the powder gases are effectively deflected towards the front.

The invention will be further described, by way of example, with reference to the accompanying drawings, in which:

FIG. 1 shows the revolving turret of an armoured vehicle with rigidly mounted machine gun,

FIG. 2 shows the recoil booster with annular shoulder.

2

In the revolving turret 1 of an armoured vehicle is mounted the vertically pivotable shield 2 for the gun barrel (not shown) and for a machine gun. To provide protection against enemy fire, the shield has an outside screen 3. The machine gun has within the zone of the muzzle a recoil booster 5, connected by a thread with the housing, and carrying on its rear end an annular shoulder 6 with spherically shaped circumference. This annular shoulder 6 is located longitudinally displaceably in a cylindrical bore 7 of the screen; in this way the muzzle of the weapon is articulatedly and also longitudinally displaceably located in the screen. Apart from that, the machine gun is mounted longitudinally displaceably in a slide 8 in order to absorb the recoil movements; the slide 8 is connected with the carriage base 9. Slide 8 and base 9 from the mounting which is equipped with an adjusting device in order to adjust the machine gun in height and laterally. This mounting is fixed by means of bolts 11, located in oblong holes 10, to the cradle 12 of the gun barrel (not shown). After unscrewing these bolts, the mounting may be adjusted by means of an adjusting screw 13, resting against a pin 14 mounted on the cradle, so as to provide adjustment in height, whilst the entire mounting with the rear end of the machine gun may swivel in the vertical plane upwardly and downwardly about the annular shoulder. The lateral adjustment is effected in the same manner by means of an adjusting screw 15 after unscrewing bolts 16, by means of which the slide is mounted to the mounting base. However, in this case, the slide 8 moves merely with the rear end of the machine gun relative to the mounting base in the horizontal plane.

FIG. 2 shows the recoil booster 5, connected by thread with the weapon housing in the muzzle region, that is to say, rigidly connected with the weapon. Immediately behind the lateral openings 17 for the powder gases, the annular shoulder 6 is located and connected by welding with the recoil booster. As may be seen from the drawing, the annular shoulder has an arcuate recess 18 within the zone of the outlets 17. In this way, the powder gases are reliably deflected towards the front.

What I claim is:

1. A mounting for machine guns in turrets of armoured vehicles, comprising a gun shield having a screen with a cylindrical bore therein, a recoil booster on a muzzle of the gun and having an externally part-spherical annular shoulder mounted in the bore with the shoulder in contact with the bore so that the booster is universally movable and axially displaceable in the bore, and said shoulder forming a pivot bearing for the recoil booster.
2. A mounting according to claim 1, in which the recoil booster is provided with a plurality of lateral outlets immediately behind the annular shoulder for the escape of the powder gases by deflection towards the front.
3. A mounting according to claim 1, in which the recoil booster is provided with a plurality of lateral outlets immediately behind the annular shoulder for the escape of the powder gases by deflection towards the front, and in which the annular shoulder has an arcuate recess open towards the front and cooperating with the lateral outlets.
